UNITED STATES PATENT OFFICE.

FRANK H. HOUGHLAND, OF CINCINNATI, OHIO; LILLIAN HOUGHLAND ADMINISTRATRIX OF SAID FRANK H. HOUGHLAND, DECEASED, ASSIGNOR TO WILLIAM F. ZENT, OF MEMPHIS, TENNESSEE.

ADHESIVE BINDING STRIP FOR CLOSING AND RECLOSED PACKAGES.

Application filed November 7, 1921. Serial No. 513,523.

To all whom it may concern:

Be it known that I, FRANK H. HOUGHLAND, a citizen of the United States, residing at Cincinnati, in the county of Hamilton and State of Ohio, have invented certain new and useful Improvements in Adhesive Binding Strips for Closing and Reclosing Packages, of which the following is a specification.

10 My invention relates to means for closing and reclosing packages for general use but is particularly adapted for use in closing and reclosing parcel post packages and packages for sending goods by express or otherwise and especially when it is desired 15 to use the carton or box for return or reshipping.

The objects of my invention are to provide simple and convenient means for securely closing and conveniently opening and reclosing packages without the use of strings or cords to interfere with the convenient handling of the packages and without mutilating said packages and also to furnish inexpensive means for this purpose that will 25 be neat and render the packages convenient for handling.

My invention consists in providing closing binding strips preferably of adhesive 30 paper, cloth or other similar material which is adapted to be pasted across the flap or lid of the package and the body thereof when the lid or package is in closed position, whereby said package is held closed; and 35 it consists further in providing a reclosing adhesive binding strip or sticker which has directions upon one end for using the closing binding strip and reclosing binding strip, said direction end being pasted 40 upon the outside of the package and having its other end extending into the package and inaccessible until the package is opened by cutting the closing binding strip, whereupon the reclosing binding strip may be detached 45 and used for reclosing the package, or if desired, the directions may be pasted or printed directly upon the outside of the package and a detached reclosing adhesive binding strip placed within the closed pack- 50 age.

My invention further consists in the con-

struction, combination, and arrangement of parts as herein set forth and claimed.

In the drawings:

Fig. 1 is a perspective view of a closed 55 box showing my invention applied thereto;

Fig. 2 is a perspective view of the same in open position ready to be filled and closed by means of my invention;

Fig. 3 is a perspective view of a telescoping type of box in open position after having been once closed;

Fig. 4 is a view of the same in reversed position showing one part of the box partly 65 inserted into the other;

Fig. 5 is an enlarged view of a reclosing adhesive binding strip and directions;

Fig. 6 is a perspective view of a box held in closed position by a closing adhesive binding strip and showing the directions on top 70 of the box with the reclosing adhesive binding strip extending into the box;

Fig. 7 is a perspective view of a box in open position and having a reinforcing contents holding box therein partly removed 75 and showing my closing adhesive binding strip severed and the reclosing binding strip in position within the box ready for reclosing it;

Fig. 8 is a perspective view of a box held 80 in closed position with my closing adhesive binding strip having the directions printed thereon;

Fig. 9 is a perspective view of one end of the box shown in Fig. 8 after having been 85 opened by tearing or cutting the closing adhesive binding strip and showing the reclosing adhesive binding strip resting against the contents of the box ready for rebinding it in closed position;

Fig. 10 is a section on the line 10-10 of Fig. 6;

Fig. 11 is a plan view of the directions;

Fig. 12 is a plan view of the adhesive closing strip; and

Fig. 13 is a plan view of the adhesive reclosing strip.

In the embodiment of my invention, as illustrated and which shows preferred constructions, I provide a closing adhesive binding strip 1, attached to the body of the package such as 2 and to the folding flaps

3 and 4 respectively, to secure the box in closed position as shown in Fig. 1. The directions 5 as shown in Figs. 1 and 2 are pasted upon the side of the box and a reclosing adhesive binding strip 6 is attached thereto and adapted to be folded inwardly upon closing flaps 7 and 8, and beneath closing flaps 3 and 4 respectively, so that when the box is in closed position, the reclosing adhesive binding strip will be concealed and also held out of contact with the contents of the box as shown in Fig. 2. The reclosing adhesive binding strip is preferably provided with perforations 9, at its junction with the direction end 10 to permit it to be readily detached therefrom for use in reclosing the box, said reclosing adhesive binding strip being placed over or in the same position occupied by the adhesive closing binding strip shown in Fig. 1.

Various modifications in the application and use of my invention may be employed, as illustrated in the several views, as, for instance, when a telescoping box such as 25 illustrated in Figs. 3 and 4 is used, the directions 5 may be pasted or printed upon the box independently of the closing adhesive binding strip 1 as shown in Fig. 4, and the reclosing adhesive binding strip 6 as 30 shown in Figs. 3 and 4, both being separate from the directions thus permitting the unprinted adhesive binding and rebinding strips to be cut in varying lengths, depending upon the size and kind of box used.

When the box is provided with flaps 11 and 12 which fold inwardly towards each other with flaps 13 and 14 which extend inwardly towards each other without overlapping, I prefer to use the directions 5 having 40 the adhesive rebinding strip 6 attached thereto, said directions being pasted upon the top of the box as shown in Figs. 6 and 7 with the rebinding strip extending and concealed within the box and having the closing adhesive binding strip 1' pasted across the flaps 13 and 14 and upon the ends of the sides of the box as shown in Figs. 6 and 7.

Or the closing adhesive binding strip 1" may have the directions printed upon its entire outer surface as shown in Fig. 8 with the reclosing adhesive binding strip 6" concealed within the end of the box upon the contents 15, as shown in Fig. 9. Other variations may be made, depending upon the 55 particular type of box used.

To use my invention, attach the directions to the box, as shown in Figs. 1, 3 and 4 independently of the binding strip or to place the directions upon one end of the reclosing binding strip, as shown in Figs. 2, 6 and 7 or upon the closing binding strip, as shown in Fig. 8.

To close the box either place the reclosing binding strip partly within the box as shown 65 in Figs. 6, 7 and 10, or entirely within the

box and upon the contents as shown in Figs. 3 and 9. Then fold the flaps inwardly towards each other and seal them in closed position by the closing adhesive binding strip, as shown in Figs. 1, 6 and 8. To open the 70 box slit the adhesive closing binding strip adjacent the edge of the flaps to which it is attached, or at the edge of the lid or cover of the box, as the case may be, whereupon the box may be opened for inspection or for 75 removing the contents and refilling. To reclose the box use the reclosing binding strip upon the inside of the box or detach the reclosing adhesive binding strip on the perforated line if it is attached to the direction 80 end of the strip and close it by means of the adhesive material thereon in or over substantially the same position which was occupied by the closing adhesive binding strip.

When the directions are printed or pasted directly upon the box independently of the binding or rebinding strips both the binding and rebinding strips may be cut from a roll to the desired length depending upon the size of the box, thus economically and conveniently adapting my invention to all kinds and sizes of boxes.

The length and width and character of the binding strips will be governed by the size and character of the contents of the box, 95 as for instance, a large heavy box will be preferably secured by heavy adhesive paper, tape or cloth or other strong material as may be desired, whereas a smaller box with light contents will be sufficiently secured in closed position by means of ordinary strips of adhesive paper or similar material.

My invention is of great convenience and advantage to the parcel post authorities who may have occasion to inspect the contents of the package, as this furnishes a 105 convenient and rapid means of opening and closing a package or box and of always maintaining the box in a neat and securely closed condition both before and after inspection. No mutilation whatever occurs to the box itself but only to the closing binding strip which upon closing with the reclosing binding strip is entirely concealed making the package as neat in appearance after 110 inspection as before. The wording of the directions may be varied or changed to suit the particular type of box as indicated on the drawings.

Some of the advantages of my invention are economy in the use of closing and reclosing binding strips as compared with other means. It makes a neat, rigid and classy package, requires no wrapping or tying of strings, hence no loose flaps, strings or paper to catch. It is not bulky and hence requires less space in the mails. It can be opened and reclosed more readily than a string wrapped and tied package. No mutilation of the package occurs in opening 120 125 130

and reclosing, the package remaining in the same condition as when mailed. It furnishes absolute protection to the contents. Another very important advantage is that 5 while a package is securely closed to prevent leakage or exposure of the contents it is not sealed to the parcel post authorities, since the closing binding strip may be severed according to directions, the contents 10 examined and the package may then be again securely closed by the reclosing binding strip, all according to the plain directions upon every package.

A feature of the invention consists of the 15 directions attached to the outside of the package either separately or attached to the adhesive binding strip.

What I claim as new and desire to secure by Letters Patent is:

20 1. Means for closing and reclosing a package, comprising directions, a reclosing binding strip detachably connected to the directions and partly concealed within the package, a binding strip for closing said package and means for adhesively attaching 25 said directions and binding strip to the package, substantially as set forth and for the purposes specified.

2. Means for closing and reclosing a pack-

age, comprising an adhesive binding strip 30 adapted to secure the lid or flap of said package in fixed relation to the body thereof whereby said package is closed, and an adhesive binding strip having directions 35 printed upon a portion thereof, said direction portion being secured to the outside of the package and having the other portion of said adhesive binding strip extending within 40 said package and concealed therein, for the purposes set forth.

3. Means for closing and reclosing a package, comprising an adhesive closing binding strip adapted to close a package, said package being adapted to be opened by severing said adhesive binding strip at a 45 point along the edge or lid of the flap and an adhesive reclosing binding strip having directions printed upon a portion thereof and secured in exposed position on the outside 50 of the box and having the other portion of said adhesive reclosing binding strip extending within the package, and a line of perforations across said reclosing binding strip along the edge of the package whereby said reclosing binding strip can be 55 secured after the package has been opened for the purpose of reclosing the package.

FRANK H. HOUGHLAND.
